UNITED STATES PATENT OFFICE.

FRANK B. DEMING, OF SALEM, OHIO.

HUB-BORING MACHINE.

SPECIFICATION forming part of Letters Patent No. 374,945, dated December 20, 1887.

Application filed October 11, 1886. Serial No. 215,874. (No model.)

To all whom it may concern:

Be it known that I, FRANK B. DEMING, a citizen of the United States, residing at Salem, in the county of Columbiana and State of Ohio, have invented certain new and useful Improvements in Hub-Boring Machines; and I do hereby declare that the following is a full, clear, and exact description of the invention, which will enable others skilled in the art to which it appertains to make and use the same.

My invention relates to improvements in hub-boring machines of the class in which the hub is revolved and the boring-shaft has rectilinear, but not rotary, movement.

15 The invention consists in the construction shown and described, and particularly pointed out in the claims.

Referring to the drawings, Figure 1 is a perspective of the machine. Fig. 2 is a longitudinal vertical section thereof. Fig. 3 is a view showing the feed-nut and cap in detail. Fig. 4 is a perspective of the chuck-head with the scroll-plate removed. Fig. 5 is a view of the threaded side of the scroll-plate in perspective, 25 and Fig. 6 shows a section of the clamping mechanism at the heel of the swinging bearing on the line xz , Fig. 2.

A represents the supporting bed or frame of the machine provided with vertical face-plate 30 a at its front, cut out annularly to form an opening for attaching and operating the hub and wheel-clamping mechanism secured therein.

B is a swinging bearing for the boring-shaft, having arms b , pivoted in ears on the back of the face-plate a and adjustably supported at its rear on the guide-plate C. The plate C is set upon its edge and screwed to the base through flanges or ears at its side.

40 At its inner end is a perforation, c , occupied by the adjusting and clamping screw D. The screw D is provided with a large milled head, to facilitate turning, and a pinion, d , inside the head, which is adapted to work in the elliptical slot b' in the heel of the swinging bearing B. The slot b' has gear or cog rack at one side, whereby, when the screw D is turned, the pinion will work in the ratchet or cog rack, and adjust the bearing higher or 45 lower at that point, as may be desired. A nut, b^2 , Fig. 6, on the opposite end of the screw, serves to clamp and hold the parts in

adjusted position. The bearing B is further provided with a socket, b^3 , vertically in its center, and a yoke, b^4 , rising from the sides of 55 the socket and having sufficient elevation to permit the necessary adjustment of the boring-shaft, as will be described hereinafter.

E is the boring or cutter shaft, screw-threaded about its outer portion, and suitably 60 constructed at its inner end for attaching the bits or cutters. This shaft is incased throughout its greater length in a sleeve, G, which in turn rests in a hub, H, that encircles the sleeve, and has a trunnion, h , supporting the hub in 65 the socket b^3 of the bearing B. A handled screw, I, passes through the arch of the yoke b^4 , into the hub H, to raise or lower it in the socket, and thereby adjust the cutter-shaft to any desired elevation in determining the size 70 of the bore. The outer end of the cutter-shaft is swiveled in a standard, K, having a bifurcated end embracing the guide-plate and adapted to ride thereon as the shaft is adjusted in either direction.

75 L is the clamping-head, having the inwardly-projecting annular flange l , which fits within the opening in the face-plate a and forms a casing for the scroll-plate M. The head L has a central opening, l' , and slots l'' radiating 80 therefrom, in which are located the dogs n . These dogs have grooves in their edges, which hold them in the slots, and teeth on their inner sides to engage with the threads m on the scroll-plate. When the parts are placed in 85 working position on the supporting-frame, they are held together and secured to the face-plate of the frame by clips and bolts n' .

On the periphery of the clamping or chuck head are bolted short arms l^1 , having suitable 90 screw-holders, l^2 , for the spokes of the wheel, and a handle, l^3 , on one of the arms for turning the head during the operation of boring. A pin, l^4 , on the inside of the chuck-head projects through the opening in the scroll-plate 95 and engages a pin, o' , on the collar o on the inner end of the sleeve G. The pin o' is pivoted, so that it can readily be thrown into or out of engagement with the pin l^4 , and a set-screw fixes the collar o on the sleeve.

100 P is the feed-nut, formed in two separate sections, p p , pivoted, respectively, on the head of the sleeve G at p' , and having screw-heads or projections p^2 , which enter the eccentric

- slots q in the cap Q. A set-screw, q' , on the cap Q is adapted to work in an annular groove in the head of the sleeve to fasten the cap thereon and hold it on the feed-nut. The cap has
- 5 an opening through which the cutter-shaft is free to slide without engaging the threads, and by means of its eccentric slots and the screw-heads on the nut working therein serves to throw the nut into or out of engagement
- 10 with the shaft. It is the work of an instant to turn the nut and effect either result, as may be desired. The scroll-plate has two or more bosses, m' , at intervals on its outer face, into which a lever or bar may be inserted for turning said plate and adjusting the dogs toward or from the center, according as the hub is to be fastened or released. The dogs being set by this means will be held there by the scroll-plate, and all the parts will revolve together
- 15 with the chuck-head when turned.
- The screw D and its associated mechanism is designed to regulate the taper of the bore, and the screw I in the yoke of the bearing to regulate the cut as to size. The range of adjustment in both cases is ample for all practical purposes, and the degree of adjustment can by the mechanism thus provided be regulated with fineness and accuracy.
- 20 The operation of the machine will be obvious from the foregoing description. The cutter having been set to do the desired work, the feed-nut and the pins r' and o' thrown into engagement, and the head L being revolved, the cutter-shaft will be fed forward into the wheel-hub by the feed-nut turning on the screw-threaded outer shaft. The sleeve G of course will be turned by the action of the chuck-head; but the cutter-shaft will simply have a longitudinal movement.
- 25 Having thus described my invention, what I claim, and desire to secure by Letters Patent, is—
1. In a hub-boring machine, a supporting-frame, a bearing adjustable on said frame, a hub adjustable in said bearing, a sleeve passing through the hub, and a cutter-shaft extending through the sleeve, substantially as set forth.
- 30 2. In a hub-boring machine, a pivoted bearing and a hub set into said bearing and independently adjustable therein, in combination with a sleeve constructed to turn in the hub, and a cutter-shaft in the sleeve and longitudinally adjustable therein, substantially as set forth.
- 35

3. In a hub-boring machine, a main frame, a bearing for the cutter-shaft adjustable in a circle on said frame, whereby the taper of the bore is regulated, a cutter-shaft, and a support therefor adjustable on the aforesaid bearing to regulate the diameter of the cut in the hub, in combination with a sleeve upon the cutter-shaft, and mechanism for turning the sleeve and feeding the cutter, substantially as set forth.

4. In a hub-boring machine, a cutter-shaft, a sleeve for feeding the cutter, and a support for said parts pivoted and adjustable on the main frame, in combination with a hub in which the sleeve is constructed to turn and which is adjustable upon the aforesaid support, whereby the position of the cutter-shaft as to pitch and diameter of cut may be regulated, substantially as set forth.

5. In a hub-boring machine, a supporting-frame, a bearing for the cutter-shaft pivoted thereon and having a socket and yoke, in combination with a hub adjustable in the socket, and a sleeve for the cutter-shaft extending through the hub, substantially as set forth.

6. In a hub-boring machine, a yoke pivoted on the main frame at one side and adjustable on the other and a hub vertically adjustable in the yoke, in combination with a cutter-shaft and a feeding-sleeve supported in the yoke, substantially as set forth.

7. In a hub-boring machine, a bearing-frame, a hub for carrying the cutter-shaft, and an adjusting device in the bearing-frame to raise and lower the hub independent of said frame, in combination with a cutter-shaft and a sleeve passing through the hub, substantially as set forth.

8. In a hub-boring machine, a screw-threaded cutter-shaft and a sleeve thereon having a head at its outer end, in combination with a sectional nut, the sections of which are separately pivoted on the face of said head and have projections which work in eccentric slots in a cap, and said cap, which incloses said nut and the sleeve-head, substantially as set forth.

In testimony whereof I sign this specification, in the presence of two witnesses, this 5th day of October, 1886.

FRANK B. DEMING.
